WARE.

METHOD AND APPARATUS FOR WIRELESS SIGNALING.

1,365,787.

Specification of Letters Patent. Patented Jan. 18, 1921.

Application filed August 2, 1915. Serial No. 43,182.

To all whom it may concern:

Be it known that I, FRED H. KROGER, a resident of Brooklyn, in the county of Kings and State of New York, have invented a new and useful Improvement in Methods and Apparatus for Wireless Signaling, of which the following is a specification.

This invention relates to a method of and apparatus for generating radio signals by the use of a quenched spark gap.

The object of the invention is a more perfect tone control so as to obtain in the receiver a substantially pure or unvarying note when using a quenched spark gap in the transmitting apparatus, the purity of the note being independent of exact adjustment of the voltage of the generator, or of the frequency or coupling value in the oscillation circuits; and enabling the generator to be worked at a low excitation value.

In the drawings, which represent one embodiment of the invention, Figure 1 is a diagrammatic view of the circuits; Fig. 2 is a diagram showing the fall of potential across the spark gap when my improved spark control circuit is omitted; and Fig. 3 is a similar view showing the potential curve when the spark control circuit is used.

The apparatus illustrated for carrying out the invention comprises a power circuit 1 supplied from an alternating current generator 2 and provided with the usual operating key 3, and being suitably connected to the oscillating circuit 4, such as by the usual transformer 5. The primary oscillating circuit includes a capacity 6, the quenched spark gap 10, and the primary 8 of the oscillation transformer, the secondary 9 of which is in the antenna circuit. The units of the primary oscillating circuit are all connected in series. The spark control device shown comprises a step-up transformer whose primary 11 is in the power circuit 1 in series with the primary of the transformer 5, and the secondary 12 is in a control circuit 13 which is connected across part of the quenched spark gap 10. The primary 11 has a small number of turns while the secondary 12 has a large number of turns, said coils being inductively connected by being wound upon a common iron core.

Oscillograms have shown that when cer-

tain relations exist between the constants of the various units in Fig. 1, efficient operation obtains if the spark in the quenched gap 10 occurs at a properly chosen instant when the current in the primary of the transformer circuit is in the vicinity of its zero value.

The magnetic flux in the iron core of the series transformer 11, 12 tends to follow the current in the power circuit and since the counter E. M. F. of the transformer is proportional to the rate of change of the magnetic flux, the counter E. M. F. is a maximum when the magnetic flux, and therefore the current, passes through the zero value. Thus the voltage on the secondary 12 of the series transformer will be a maximum when the current in the power circuit passes through zero. The secondary voltage of the control circuit 13 is impressed upon the part of the spark gap 10 to which said circuit is connected and has the effect of increasing the potential gradient on that portion of the spark gap to a value of voltage gradient which compels the production of a spark, and said circuit acts as a trigger to trip off the main spark across the entire gap at the same instant in each half cycle, so that a uniform succession of regularly and evenly spaced sparks is produced.

Why this is so, is illustrated by the diagrams of Figs. 1 and 2. These figures illustrate that portion of the oscillating circuit 4 containing the capacity 6 and spark gap 10, Fig. 2 showing this circuit with the spark control omitted, while Fig. 3 shows the spark control circuit connected across a part of the spark gap as in Fig. 1. In the curve diagrams shown in connection with each figure, the ordinates are the number of gaps measured from the bottom of the gap 10 as a point of reference, and the abscissae are electromotive forces measured from the bottom of the gap as a point of reference, the left-hand vertical dotted line passing through zero and the distance between said line and the right-hand vertical dotted line representing the electromotive force from the bottom to the top of the gap 10.

With the control circuit omitted, as in Fig. 2, the curve A in the diagram indicates the fall of potential across the gap, and a point on the curve A represents the electromotive

force at a certain number of gaps from the bottom as indicated by the ordinate of that point. The potential gradient shown by curve A is greater than the power transformer can build up across the gap in the time equivalent to one alternation of the generator current subsequent to a discharge of the condenser, unless the generator is operated at a high field excitation value. 5

10 But where the number of gaps is selected so that the potential applied each half cycle will cause a single spark, the excitation of the generator above the critical point leads to the production of more than one spark per alternation. But with the usual apparatus an even greater difficulty is often encountered, to-wit, that of obtaining the sparks of succeeding alternations at the same instant in each half cycle, or, in other words, at the 15 same point in the voltage wave. Consequently, in the usual arrangements the time intervals between sparks are irregular and a rough or varying note is heard in the receiver.

20 25 Now, with the arrangement shown in Fig. 3, the control circuit impresses an additional voltage upon a part of the spark gap, and since the phasing of the transformer 12 as related to the transformer 5 is such that the polarity produced by it is, at any instant, opposite to the polarity of transformer 5, the electromotive force across the lower section of the gap is represented by the curve B which slopes to the left of the 30 left-hand vertical dotted line. The main transformer 5 produces across the gap 10 an electromotive force E_1 , while the auxiliary transformer 12 produces across the small section of the gap an electromotive force E_2 , opposite in polarity to the electromotive force E_1 . The sum of these two 35 electromotive forces gives across the upper larger section of the gap a potential difference E_s , which is larger than E_1 , while the number of gaps to withstand this larger electromotive force E_s is less than the number 40 of gaps to withstand the smaller electromotive force E_1 when the auxiliary transformer is not used. Consequently, since the 45 auxiliary transformer produces its electromotive force E_2 for a short interval of time as compared with the time of one alternation, the electrical strain on the upper larger section of the gap becomes great enough to 50 break down that part of the gap and, in turn, the smaller section breaks down, allowing the discharge to take place. The potential gradient across the upper larger section of the gap is represented by the curve C, whose 55 inclination is much greater than that of the corresponding curve A in Fig. 2, and this effective increase in the potential gradient is sufficient to cause the gap to discharge and produce its train of waves. 60

Nevertheless the generator may be operated at a normal excitation value below the critical point and without liability of producing a plurality of sparks in any one alternation. The trigger control secondary 12 causes its increase in potential gradient 65 across the gap each time the primary current of the power transformer passes through zero, which occurs each alternation. Consequently a condenser discharge occurs 70 each alternation at the instant when the trigger control circuit trips off the spark and opens the way for the flow of the main current. In order that the potential of the secondary 12 may occur at a definite instant 75 in each half cycle and thereby produce an even succession of sparks the wave form of the secondary is preferably made very peaked by saturating the iron core of the tone control transformer. One suitable form of transformer has a primary of 30 turns and a secondary of 8000 turns, the current 80 in the primary at full load being 5 amperes. The core is laminated, having 48 laminations, each .014 inch thick, and the magnetic circuit is of rectangular form. 85

90 In some cases it may be advisable to utilize a suitable capacity 15 in the tone control circuit 13 to limit the amount of current which can flow in the trigger or control circuit 13, but this is not always essential and 95 in many cases may be omitted.

99 What I claim is:

1. The method of producing sparks at regularly recurring intervals, which consists in impressing on a spark gap a normal 100 alternating voltage, and, in addition, an audio frequency voltage impulse at a definite instant in each half cycle of the normal voltage, to thereby cause the gap to break down at regular intervals. 105

2. The method of producing electrical oscillations by a spark discharge at regularly recurring intervals, which consists in impressing on part of a quenched spark gap in an oscillating circuit a normal alternating voltage, and, in addition, an audio frequency voltage impulse at a definite instant in each half cycle of the normal voltage, to thereby cause said gap to break down at regular intervals and produce oscillations 110 in the oscillating circuit. 115

3. The method of producing sparks at regularly recurring intervals for generating oscillations in a circuit containing a spark gap, which consists in applying to a part 120 of the spark gap, at regular intervals, audio frequency voltage impulses derived from the main current source.

4. Apparatus for producing oscillations, comprising an oscillating circuit containing a spark gap, a generator circuit for supplying power thereto, and a circuit derived 125 from the generator circuit and including

part of said gap for impressing an audio frequency voltage impulse thereon to break down said gap at regular intervals.

5. Apparatus for producing oscillations, comprising an oscillating circuit containing a spark gap, a generator circuit for supplying power thereto, and a circuit connecting said power circuit and part of said spark gap for applying a single audio frequency voltage impulse periodically to the gap and thereby breaking it down at regular intervals.

6. Apparatus for producing oscillations, comprising an oscillating circuit containing a spark gap, a generator circuit, a transformer connecting said circuits, a circuit including part of said gap, and a transformer in series with the first-named transformer and including a secondary connected across part of said gap, said second transformer producing single audio frequency impulses which are impressed directly upon the spark gap and break down said gap at regular intervals.

25 7. The method of producing sparks at regularly recurring intervals in an oscillating circuit containing a spark gap, which consists in impressing an alternating voltage upon said circuit, and impressing a single audio frequency impulse derived from the main alternating current source upon the spark gap at a definite instant in each half cycle of the alternating voltage.

8. The method of producing sparks at regularly recurring intervals in an oscillating circuit containing an air gap which consists in impressing an alternating voltage upon said circuit and impressing an additional voltage upon a portion of the spark gap at a definite instant in each half cycle of the alternating voltage, the polarity of the extra voltage being opposite to the polarity of the main voltage at the instant it is impressed upon the spark gap.

45 9. The method of producing sparks at regularly recurring intervals in an oscillating circuit having a quenched spark gap which consists in impressing an alternating voltage upon said circuit and impressing an audio frequency voltage impulse derived from the main alternating current source upon a part of the quenched spark gap at a definite instant in each half cycle of the alternating voltage thereby causing said gap to break down at regular intervals and produce oscillations in the oscillating circuit.

10. The method of producing sparks at regularly recurring intervals in an oscillating circuit having a quenched spark gap which consists in impressing alternating voltage upon said circuit and impressing an extra voltage upon a part of the quenched spark gap at a definite instant in each half cycle of the alternating voltage, the polarity

of the extra voltage being opposed to that of the main voltage at the instant it is impressed on the gap whereby the gap is tripped off at regular intervals.

11. Apparatus for producing electrical oscillations comprising an oscillating circuit containing a spark gap, a generator circuit for supplying alternating voltage thereto, and means for impressing a single audio frequency voltage impulse, derived from the main alternating current source, upon a portion of the spark gap at a definite instant in each half cycle of the alternating voltage applied to the oscillating circuit.

12. Apparatus for producing electrical oscillations comprising an oscillating circuit containing a spark gap, a generator circuit for supplying power thereto, and means for impressing an extra voltage upon a portion of the spark gap at a definite instant in each half cycle of the alternating voltage applied to the oscillating circuit, said extra voltage being of opposite polarity to the main voltage at the instant it is impressed.

13. Apparatus for producing electrical oscillations comprising an oscillating circuit containing a spark gap, an alternating current generator circuit for supplying power thereto, and means energized by the generator circuit for impressing an audio frequency voltage impulse, derived from the main alternating current source, upon a portion of the spark gap at a definite instant in each half cycle of the alternating potential.

14. Apparatus for producing electrical oscillations comprising an oscillating circuit containing a spark gap, an alternating current generator circuit for supplying power thereto, and means energized by the generator circuit for impressing an extra voltage upon a portion of the spark gap at a definite instant in each half cycle of the alternating potential, said extra voltage being of opposite polarity to that of the main voltage at the instant it is impressed.

15. Apparatus for producing electrical oscillations comprising an oscillating circuit containing a spark gap, an alternating current generator circuit for supplying power thereto, and a third circuit inductively connected to the generator circuit by a series transformer arranged to give a peaked wave form, said third circuit being connected across a portion of the spark gap, whereby an audio frequency voltage impulse is suddenly impressed upon a portion of the spark gap at a definite instant in each half cycle of the alternating potential.

16. Apparatus for producing electrical oscillations comprising an oscillating circuit containing a spark gap, a generator

circuit inductively connected to the oscillating circuit for supplying alternating energy thereto, a third circuit connected to the generator circuit by a series transformer adapted to give a peaked wave form, said third circuit being connected to a portion of the spark gap so that an extra voltage of opposite polarity to the main voltage across the spark gap is suddenly impressed upon a

portion of the spark gap at a definite instant 10 in each half cycle to thereby trip off the spark gap at regular intervals.

In testimony whereof, I have hereunto set my hand.
